UNITED STATES PATENT OFFICE.

DANIEL S. SEBASTIAN, OF WALLACE, IDAHO, ASSIGNOR OF ONE-HALF TO
PETER BERNIER, OF WALLACE, IDAHO.

FIRE-ESCAPE.

No. 801,614.

Specification of Letters Patent.

Patented Oct. 10, 1905.

Application filed September 9, 1904. Serial No. 223,863.

To all whom it may concern:

Be it known that I, DANIEL S. SEBASTIAN, a citizen of the United States, and a resident of Wallace, in the county of Shoshone and State 5 of Idaho, have invented a new and Improved Fire-Escape, of which the following is a full, clear, and exact description.

This invention relates to improvements in fire-escapes, the object being to provide a 10 portable fire-escape of novel construction that may be quickly raised and lowered and also leveled or tilted laterally when necessary.

I will describe a fire-escape embodying my invention and then point out the novel features in the appended claims.

Reference is to be had to the accompanying drawings, forming a part of this specification, in which similar characters of reference indicate corresponding parts in all the figures.

20 Figure 1 is a perspective view of a fire-escape embodying my invention in use. Fig. 2 is a sectional elevation thereof, showing the fire-escape in raised position. Fig. 3 is a section on the line 3 3 of Fig. 2, showing the device in lowered position. Fig. 4 is a sectional view showing the raising and lowering mechanism. Fig. 5 is a plan illustrating the raising and lowering cams, and Fig. 6 indicates the fire-escape in tilted position.

30 Referring to the drawings, 5 designates a truck-frame mounted on wheels 6, and arranged to rock on this truck-frame is a platform 7. As here shown, this platform has lugs 8 at its ends, through which a rod 9 passes, said rod being connected at its ends with the end boards of the body or frame 5. Having bearings in the end boards of the body or frame and near the sides are shafts 10 11, on which eccentrics 12 13 are mounted, these 35 eccentrics being designed to engage with the under side of the platform 7. At the rear end the shafts 10 11 are provided with sprocket-wheels 14 15, engaged by a sprocket-chain 16, and one of the shafts has an operating-lever 17. By swinging the lever it is obvious that the platform 7 may be rocked to bring it on a level should the truck happen to be on a grade, or the platform may be swung to such position as to tilt the fire-escape 40 toward a building, as indicated in Figs. 1 and 6. To prevent tipping over of the truck, I provide anchoring devices consisting of telescopic rods 18 19, mounted to swing underneath the body 5 and outward to the

side thereof. The outer member 19 of each 55 rod has a threaded ring 20 for receiving a screw-shaft 21, having a swiveled lower end 22. When these devices are not in use or when the fire-escape is being drawn along, the screw-shafts may be turned to horizontal 60 position and then, with the supporting-arms, turned underneath the body 5.

Extended upward from the platform 7 are posts 23 24, and pivotally connected to these posts are the inner ends of the lower links of 65 lazy-tongs 25, the outer ends of certain of the opposite links having swinging connection with cross-bars 26. The outer ends of the upper links are connected to cross-bars 27, and on these cross-bars 27 are grooved pulleys 70 28, which engage on tracks 29, to which a cage 30 is secured. The opposite sides of this cage, it will be noted, are arranged to swing downward, so as to form a platform between the cage and a window-sill or the like, so that 75 people may readily pass from the window into the cage. The cage is held practically in a central position by means of springs 31, connected to the center of the cage at the bottom and also connecting the rods 27. 80

Movable upward along the posts 23 24 is an actuating-platform 32, on the body of which are short standards 33, carrying rollers 34 for engaging with the lower links of the lazy-tongs, as shown in Fig. 2. 85

Mounted to rotate around the lower portion of each post is a circular plate 35, each provided with a handle or lever 36, and the two plates are provided with intermeshing teeth 37, so that by operating one of the plates 90 through the medium of its lever the other plate may be rotated. On each plate 35 are upwardly-extended inclined planes 38, the inclined planes of a plate being opposite each other, and engaging with these planes are rollers 39, mounted in hangers 40 41, depending from the plate 32. Above the plate 35 each post is provided with a fixed collar 42, and between this collar and the under side of the plate 32 is a spiral spring 43. 95 100

In the operation when it is desired to raise the cage the plates 35 are to be rotated by means of one of the levers 36, so that the cams or inclines 38 will move the plate 32 upward, whereby the rollers 34, engaging with the lower links of the lazy-tongs, will swing said tongs in such direction as to move the cage 105 upward, and the springs 43 will aid materially

in this movement or relieve the operator from a considerable amount of manual exertion. Of course when the plates 35 are moved in the reverse direction the cage, with its load, 5 will descend by gravity.

The levers 36 are limited in their movement for moving the cage upward by means of stops 44 on the platform 7. If desired, steady-ing or guy ropes 45 may be connected to the 10 corners of the cage.

While I have described the device particu-larly as a fire-escape, it is obvious that it will be found convenient for the use of linemen in stringing wires or making overhead repairs.

15 Having thus described my invention, I claim as new and desire to secure by Letters Patent—

1. A fire-escape, comprising a support, lazy-tongs pivoted on the support and provided with a carrier at its upper end, a vertically-movable member provided on its upper face with means for engaging the lower links of the lazy-tongs intermediate of their ends, and means for operating the said movable member.

25 2. A fire-escape comprising a truck, posts extended upward from the truck, lazy-tongs having their lower links pivotally connected to said posts, a plate movable vertically along the posts, rollers carried by said plate and 30 engaging with the lower links of the lazy-tongs, cams for causing the vertical movement of said plate, and a cage carried by the lazy-tongs.

3. A fire-escape comprising a truck, posts 35 extended upward from the truck, a plate movable vertically along the posts, lazy-tongs having their lower links pivoted to said posts, rollers carried by a plate and engaging with said lower links, plates mounted to rotate on 40 the posts, inclined planes carried by the vertically-movable plate and engaging with said inclined planes, and a cage supported by the lazy-tongs.

4. A fire-escape comprising a truck, posts 45 extended upward from the truck, plates mounted to rotate around the lower ends of said posts and having gear connections one plate with the other, opposite inclined planes carried by each plate, a plate movable vertically along the posts, rollers carried by said 50 vertically-movable plate and engaging the said inclined planes, springs surrounding the posts and engaging the under side of the vertically-movable plate, lazy-tongs having their lower

links pivoted to said posts, rollers mounted 55 on the vertically-movable plate and engaging with said lower links, a cage, tracks secured to the under side of said cage, and rollers carried by the outer ends of the upper links and engaging with said tracks.

5. A fire-escape comprising a wheel-mounted body, a platform mounted to rock on the body, parallel shafts below the platform and having bearing in the end boards of the body, a cam on each end of each shaft for engaging the 65 under side of the platform, sprocket-wheels on the rear ends of said shafts, a chain connection between the said wheels, a lever on the end of one shaft for operating the same, lazy-tongs supported on the platform, means 70 for causing an upward movement of the lazy-tongs, and a cage supported by said lazy-tongs.

6. The combination with a wheel-mounted body, and an extensible fire-escape mounted thereon, of telescopic bars mounted to swing 75 on the under side of the body, and screw-rods mounted in the outer end of the outer bar and provided with a foot at its lower end.

7. In a fire-escape, a support provided with 80 posts, lazy-tongs pivoted to the posts, a platform mounted loosely on the posts and provided on its upper face with means for engaging the lower links of the lazy-tongs, and co-operating means on the platform and support for raising the platform.

8. In a fire-escape, a support provided with 85 posts, lazy-tongs pivoted to the posts, a platform mounted loosely on the posts and provided on its upper face with means for engaging the lower links of the lazy-tongs, springs 90 on the posts below the platform, and means for raising the platform.

9. In a fire-escape, a support, lazy-tongs pivoted on the support and having the upper ends of the outer links connected by cross-bars, grooved pulleys on the cross-bars, a cage provided with a track formed of spaced and parallel bars connected at their ends and between which the pulleys of each cross-bar travel, and springs secured to the cage and to 100 the cross-bars of the lazy-tongs.

In testimony whereof I have signed my name to this specification in the presence of two sub-scribing witnesses.

DANIEL S. SEBASTIAN.
